(57) **CLAIM**

The ornamental design for a bookmark with tape measure, substantially as shown.

DESCRIPTION

FIG. 1 is an isometric view of a bookmark incorporating my design;

FIG. 2 is a front view thereof, showing the measuring tape in a position of use in broken lines;

FIG. 3 is a left-side view thereof;

FIG. 4 is a right-side view thereof; and,

FIG. 5 is a top plan view thereof (the bottom view being identical).

The broken lines shown in the drawings form no part of the claimed design.
